SPARK ARRESTER

Leslie R. Pyle, Chicago, Ill., assignor to Locomotive Firebox Company, Chicago, Ill., a corporation of Delaware

Application March 15, 1933, Serial No. 660,826

6 Claims. (Cl. 230—97)

This invention relates to improvements in spark arresters and it consists of the matters hereinafter described and more particularly pointed out in the appended claims.

In spark arresters of the cyclone or centrifugal casing type as heretofore employed in locomotives, the casing is disposed with its inlet facing toward the front end door of the smoke box. Such an arrangement has certain objectionable features. All products of combustion must first pass under the casing and then have to take a reverse path before entering the inlet of the casing. With such an arrangement, the draft created in the casing and which worked upon the ends of the flues, is set up or started close to the front end door. Thus all products of combustion have to take a long and tortuous path and this requires considerable draft.

Again, this arrangement required the blocking off of that part of the smoke box in which are located steam pipe and nozzle stand joints. When such joints leaked, they interfered directly with the draft action and the steam capacity was effected accordingly. Thus, pressure tight joints were there required. Again, special air tight joints were also required at those points where the steam feed pipes for the cylinders passed through the smoke box shell.

Heretofore certain parts of the arrester casing were subject to wear and one of these places was the bottom of the casing within the circle of the race ring. The other of these places was the inside extension for the stack and this wear soon produced holes. These holes require repair service otherwise live cinders are short circuited therethrough to the stack and discharged out of the same under draft action.

One of the objects of the present invention is to provide a spark arrester of this kind, which though simple in construction, is more efficient in operation and materially shortens up the path necessary for the products of combustion and reduces the necessary draft action.

A further object of the invention is to provide a spark arrester of this kind, which reduces fuel consumption and back pressure and increases the steaming and hauling capacity of the associated locomotive as well as its speed.

Still another object of the invention is to provide a spark arrester of this kind wherein impaired draft due to air leaks in the smoke box and steam leaks in steam pipe and exhaust stand base are eliminated along with all draft sparks.

The above mentioned objects of the invention as well as others, together with the many ad-

vantages thereof will more fully appear as I proceed with my specification.

In the drawing:

Fig. 1 is a vertical longitudinal sectional view through the smoke box end of a locomotive boiler embodying my improved spark arrester.

Fig. 2 is a horizontal fragmentary sectional view through the same as taken on the line 2—2 of Fig. 1.

In general, my improved spark arrester comprises a separator casing suitably supported in the smoke box with its axis coincident with that of the stack and nozzle which terminate within the casing. Said casing is provided with an inlet mouth which is located somewhat adjacent to and faces the flue sheet forming the rear end of the smoke box. Preferably the inlet for said casing is of an area greater than the combined area of the tubes and flues opening through said sheet. In said inlet are provided deflectors which give initial direction to the products of combustion as they enter the casing.

Between the inlet end of the casing and the adjacent parts of the smoke box shell is a baffle or wall which in connection with the adjacent flue sheet provides a chamber with which said inlet communicates. Furthermore said baffle effectively blocks off that part of the smoke box in which certain steam pipe and other joints are located so that even though said joints leak there is no interference with draft action.

As the inlet for the separator casing faces generally in the direction of the flue sheet, the products of combustion leaving the tubes and flues in said sheet, take the shortest and straightest path into the separator casing. When in said casing, draft action in connection with the deflectors mentioned causes the products of combustion to take a substantially circular path in their passage between said inlet and the stack extension. Thus the larger particles thereof are ground down and extinguished by their collision with each other and by their engagement with the inner surface of the casing and are then entrained by the draft action up the stack to be discharged therefrom in a manner wherein they are harmless and incapable of starting way-side fires.

Referring now in detail to that embodiment of the invention illustrated in the accompanying drawing, 1 indicates as a whole the tubular body of the smoke box shell, suitably connected at its rear end to the front end of the boiler shell 2 in any suitable manner. 3 indicates the smoke box front having the usual door 4 therein.

- 5 indicates the front flue sheet of the boiler in which the associated ends of the usual tubes or flues are secured, so as to deliver products of combustion into the smoke box. 80
- 5 6 indicates the barrel of the stack having a flanged base secured to the top of the body of the smoke box shell about the usual opening therein. Welded in said opening is a ring 7 through which a top end part of a stack extension 10 8 projects. Said extension is welded in said ring and the top extremity of said extension enters a suitable distance up into the stack barrel. The bottom end of said stack extension is flared as at 9. 85
- 15 The exhaust stand or pipe is indicated at 10. This stand or pipe rises from the bottom of the smoke box shell in line with the stack 6 and is flanged at its top end as at 11 to receive the like flange 12 of an exhaust nozzle or tip 13 of any 90 approved kind. 95
- In the smoke box shell is located a cyclonic separator casing 14. Said casing includes an upright rounded front end wall 15, upright parallel side walls 16 and 17 respectively and flat horizontal top and bottom walls 18 and 19 respectively. This casing is open at the rear so as to provide an inlet 20 which faces in the general direction of the flue sheet and is of a height and width approximating the height and width of the casing. In 100 25 said inlet are provided upright, laterally spaced deflectors 21, 22 and 23 respectively arranged to direct the incoming products of combustion toward the side 17 of the casing. Associated with the side 16 of the casing is an upright segmental wall 24 curved to form a continuation of the rounded front wall 15 of the casing. This segmental wall which extends from the top to the bottom of the casing includes an angular deflector wing 25 disposed parallel with the deflector plates 21, 22 and 23. 105
- 30 Preferably the several walls of the casing are made in sections for ease in installation and are suitably secured together in air tight relation so as to have no leaks therein. 110
- 35 40 The bottom wall 19 of the casing is provided with a depressed flange 26 which is disposed between the flanges 11 and 12 of the pipe and nozzle respectively, to there provide a tight joint. Rising from said bottom wall is a race ring 27 45 of a diameter approximating that of the bottom extremity of the flared end 9 of stack extension 8. 115
- Surrounding the stack extension is an angle bar ring 28 and secured to said stack extension within the casing a short distance below the 50 top thereof are angle brackets 29. Draw bolts 30 extend through said brackets and ring and through the top wall of the casing and when the associated nuts 31 are drawn up, the casing and stack extension are tightly secured together at 55 this point. 120
- A transversely extending wall 32, is provided between the rear end of the casing and surrounding part of the smoke box shell and divides the smoke box into front and rear compartments 33 and 34 respectively. In this respect it is pointed out that the inlet 20 for the casing which has an area somewhat greater than the combined tube or flue end area, opens into the rear compartment 34 while the interior of the casing is 60 entirely sealed off with respect to the compartment 33. This transverse wall or partition assists in supporting the casing as a whole and in connection therewith there is provided in the chamber 33, a supplementary supporting leg 35. 125
- 65 70 75 The arrangement described, provides space between the casing 14 and smoke box shell for the steam pipes 36 that lead to the cylinders. These pipes have a flanged connection 37 with superheater headers 38 in the compartment 34 of the smoke box and which headers extend through suitable openings provided therefor in the wall 32. 130
- During the operation of the locomotive, draft created in the casing by exhaust nozzle action operates directly upon the flue and tube ends opening into the compartment 34. Thus the products of combustion take a short, direct path into the casing through its inlet. As said products enter the inlet, they are directed by the deflectors toward the side wall 17 thereof to follow around the rounded front end thereof and segmental wall 24 so as to set up a whirling or centrifugal action and thus take a substantially circular path. By reason of this action, the heavier particles of the products of combustion are not only maintained in engagement with said walls but they collide with each other so that they are broken and worn down to smaller particles. These smaller particles being the lighter are gradually forced in toward the flared end 9 of the stack extension to be entrained in the blast up 135 the extension for discharge as harmless particles out through the stack. 140
- With such an arrangement it is to be noted that no draft action is present in the compartment 33 so that even though there be air or steam leaks 145 into this compartment, there is no interference presented to the draft action in the casing. As the flues open directly into compartment 34, all flues are operating at an equal rate so that the initial draft required is much less. Therefore it is possible to open up the nozzle and maintain the same draft in the firebox and at the same time this decreases the back pressure and increases locomotive speed with a given steam chest pressure. 150
- Even though holes develop in the casing that open into the chamber 33, no ill effects are presented and no live sparks can be discharged up the stack. In all, the improved arrester increases the efficiency of the locomotive, saves fuel, is subject to less wear, costs less to install and does not require that all fittings in the chamber 33 be of the most expensive kind so as to remain leak tight because no interference is set up even though leaks be present. 155
- While in describing the invention, I have referred in detail to the form, arrangement and construction of various parts thereof, the same is to be considered merely as illustrative of the preferred embodiment thereof and therefore I do not wish to be limited thereto except as may be specifically set forth in the appended claims. 160
- I claim as my invention:
1. In combination with a smoke box, a flue sheet at one end thereof, means providing a centrifugal action chamber in said smoke box having an inlet opening facing generally toward the flue sheet, a baffle wall between said casing and smoke box shell and arranged to isolate the inlet from the front portion of the smoke box, a smoke stack having an extension opening into said casing to terminate in a plane between the top and bottom of the inlet, and an exhaust nozzle associated with said stack and also opening into said casing in a manner coaxing with said stack extension to induce a centrifugal draft action in said casing. 165
  2. In combination with a smoke box, a flue sheet at one end thereof, a smoke stack having an extension arranged in the smoke box, an ex- 170

- haust nozzle in the smoke box in line with said stack extension, means providing a perpendicularly disposed, centrifugal action separator casing in said smoke box having an inlet end facing generally in the direction of said flue sheet, and a baffle wall between said casing and smoke box shell and arranged to isolate said inlet of the casing from the front portion of the smoke box, said stack extension and nozzle projecting through opposite ends of the casing and coacting to produce a centrifugal draft action in said casing the stack extension terminating in a plane between the top and bottom of the inlet. 80
- 5 3. In combination with a smoke box, a flue sheet at one end thereof, a smoke stack having an extension arranged in the smoke box, an exhaust nozzle in the smoke box in line with said stack extension, means providing a perpendicularly disposed, centrifugal action separator casing in said smoke box having an inlet end facing generally in the direction of the flue sheet, deflector plates in said inlet for directing incoming products of combustion toward one side of the casing, and a baffle wall between said casing and smoke box shell and arranged to isolate said inlet from the front portion of the smoke box, said stack extension and nozzle projecting through opposite ends of the casing and coacting to induce a centrifugal draft action in said casing the stack extension terminating in a plane between the top and bottom of the inlet. 90
- 10 4. In combination with a smoke box, a flue sheet at one end thereof, a smoke stack having an extension arranged in the smoke box, an exhaust nozzle in the smoke box in line with said stack extension, means providing a perpendicularly disposed, centrifugal action separator casing in said smoke box having an inlet end of an area approximating the combined area of the flues opening through the flue sheet and facing in the general direction of said flue sheet, means associated with said inlet for directing the incoming products of combustion toward one side of the casing, and a baffle wall between the casing and smoke box shell and arranged to isolate said inlet of the casing from the front portion of the smoke box, said stack extension and nozzle projecting through opposite ends of the casing and coacting to produce a centrifugal draft action in said casing the stack extension terminating in a plane between the top and bottom of the inlet. 95
- 15 5. In combination with a smoke box, a flue sheet at the rear end thereof, means for closing the front end of said smoke box, a partition in said smoke box dividing the same into front and rear compartments, a centrifugal action separator casing in said front compartment and having an inlet at its rear end opening through said partition so as to communicate with said rear compartment and to face toward said flue sheet, a smoke stack having its bottom end extending through the top of the casing to terminate in a plane between the top and bottom of the inlet, and a nozzle opening through the bottom of said casing and coacting with said extension in inducing a centrifugal draft action in said casing. 100
- 20 6. In combination with a smoke box, a flue sheet at the rear end thereof, means for closing the front end of said smoke box, a partition in said smoke box dividing the same into front and rear compartments, a centrifugal action separator casing in said front compartment and having an inlet at its rear end opening through said partition so as to communicate with said rear compartment and to face toward said flue sheet, means in said inlet for directing the incoming products of combustion toward one side of the casing, a smoke stack having its bottom end extending through the top of said casing to terminate in a plane between the top and bottom of the inlet, and a nozzle opening through the bottom of the casing and coacting with the extension in inducing a centrifugal draft action in 110 said casing. 115
